F. M. C. USHER

SILO PRESS

Filed Aug. 23, 1921

Patented Apr. 1, 1924.

1,438,849

UNITED STATES PATENT OFFICE.

FRANCIS M. C. USHER, OF FULTON, KENTUCKY.

SILO PRESS.

Application filed August 23, 1921. Serial No. 494,453.

To all whom it may concern:

Be it known that I, FRANCIS M. C. USHER, citizen of the United States, residing at Fulton, in the county of Fulton and State of Kentucky, have invented certain new and useful Improvements in Silo Presses, of which the following is a specification.

This invention relates to silo presses, and is for the same general purposes and of like 10 operation with silos of ordinary construction.

Those silos with which this applicant is acquainted are vertical towers with subordinate details variously formed and arranged. 15 It is believed that a much cheaper and more convenient structure would result by disposing the casing or body of the silo, made up of creosoted wood, preferably, either square or cylindrical, in a horizontal 20 position. In a horizontal position the silo may be covered with earth piled over it, or it may be sunken in the earth, and it is believed the ensilage will keep and ferment better, and be held at a more even temperature, and that it will not freeze. It is further believed that the casing of a silo arranged and embedded in earth as stated would last longer, and that it would not dry 25 and fall apart so soon. Further, and in the opinion of this applicant, a manifest and desirable advantage of the horizontal construction lies in the fact that it is very much more easy to fill and at a materially reduced cost, which is an important item in present 30 practice, and the horizontal disposition of the casing renders it especially accessible when the ensilage is to be withdrawn for feeding.

The particular construction and arrangement of the different parts of this invention are illustrated in the accompanying drawings, of which Fig. 1 represents a lengthwise and vertical section exhibiting all the parts assembled. Fig. 2 is a cross-section taken 45 on the broken line 2—2 of Fig. 1. Fig. 3 is a top plan view of a portion of the top of the casing showing the dump openings and the closures or doors therefor. Fig. 4 is a fragmentary section taken on broken line 50 4—4 of Fig. 3 and shows a temporary cover or bridge for the dump openings when it is desired to drive a team over them, as will be more fully explained hereinafter.

Throughout the drawings and explanation 55 the same letter is used to refer to the same part.

Considering the drawings, the casing or body A may be made up of longitudinal boards *a*, firmly held together by exterior bands B having band clamps *b*. It is not intended to limit this invention to the square section illustrated, or to the board construction mentioned. Creosoted boards are found to be most durable.

The top C of the casing A near its end 60 has the dump openings D and *d*, provided with suitable doors E and *e* which when closed exclude the air. At the sides of the openings are portions F and *f* of the top 65 extending transversely and affording track 70 or support for a vehicle drawn or backed over the openings to dump the material into the casing through the openings.

Fitting the casing interiorly and movable therein is a presser head G which is stoutly 75 constructed and provided with an upwardly inclined front *g*. To the presser head G are attached the two parts H and *h* of a cable. The part *h* of the cable passing to the left hand in Fig. 1 turns over the pulley *h'* and 80 is taken up by the windlass J having the operating handle *j*. By means of the windlass J the presser head G may be drawn in a direction from the right or casing door K, and past the dump openings D and *d* thus 85 enabling the materials to be dumped through the openings upon the floor or bottom of the casing into the position indicated by the dotted hyperbolic line in Fig. 1. One important function of the inclined face of the 90 presser head is its effectiveness in keeping the dump openings clear within the casing of hanging and entangled pieces of material, which always catch and hold upon the frame and crosspiece of the dump opening. It 95 will be noted in Fig. 1 that the upper front edge of the presser head is relatively a sharp edge.

The door K at the right hand end of the casing A in Fig. 1 must necessarily withstand internal pressure, and the pivoted clamping devices *k* are introduced to secure the door against the internal pressure. In Fig. 1 it will be noted that the cable H passes through the door K and is taken up 100 by a capstan L operated by the bar *l* in the common manner. It is not intended to limit this invention to any special means for actuating the presser head G in either direction, as there are a number of mechanical 105 contrivances well known that could be employed for the purpose.

In a large silo the closing door K may be of some considerable size and correspondingly heavy, and this invention contemplates the provision of a carrier bracket M and 5 roller m as illustrated in Fig. 1 by which the weight of the door when moved may be supported upon a suitable track N.

In the operation of this invention, the 10 fodder is dumped into the casing through the dump openings D and d. This may be accomplished by providing an earth incline P as shown in Fig. 2 up which a truck may be driven or backed. To protect the wooden 15 edges of the silo, projecting iron brackets O may be introduced at the sides as also shown in Fig. 3. If a truck is used it is not difficult to so direct the vehicle as to compel its wheels to follow the tracks or supports F and f at the sides of the dump openings. 20 But, in the case of a horse-drawn vehicle it may be necessary to provide the well known expedient of a temporary cover Q, as illustrated in Fig. 4 to temporarily cover the dump openings until the horses have passed 25 over and the vehicle is located as desired for dumping. Obviously, it is practicable to drive the horses and vehicle over the closed doors E and e, and to open those doors after the rear wheels of the vehicle have moved 30 far enough to permit. With a slatted dumping wagon or truck, the wheels rest upon the tracks F and f. In other words, whatever may be the character of the dumping 35 vehicle employed, the material can be deposited through the openings D and d upon the bottom of the casing as indicated by the broken line and in front of the presser head G. Upon moving the presser head to the right, the upwardly inclined front g 40 forces the materials towards the door K, and compresses the end of the contents of the casing on an incline as indicated by the slanting broken line in Fig. 1. Upon pressing further loads of material to the right in 45 the casing, the inclined front g operates to

spread the load upwardly over the end of that already compressed. It will be understood that the presser head fits the casing 50 interiorly and prevents the entrance of air from the left hand end of the casing, but it is believed to be within the scope of this invention to close that end also by any chosen means if found desirable. The doors E and e close the dump openings as already explained. 55

Having now described this invention and explained the mode of its operation, what I claim is:—

1. In a horizontal silo press, the combination with a casing horizontally disposed, of a removable door at one end of the casing, devices for securing the door against internal pressure, a presser head fitting the casing interiorly and movable therein, the said presser head having an upwardly inclined front, the said casing having a dump opening in its top, closures for the said opening, means for moving the presser head in the casing, and the upper edge of the said inclined front of the presser head being arranged to scrape the edges of the dump opening within the casing to clear the same of obstructing material. 70

2. In a horizontal silo press, the combination with a casing horizontally arranged 75 and embedded in the earth to permit vehicles to be driven upon the casing, of a removable door at one end of the casing, devices for securing the door against internal pressure, the said casing having a dump 80 opening in its top, the said dump opening being provided on both sides of the casing exteriorly with attachments for protecting the edges of the casing from injury by vehicle wheels, a presser head fitting the casing interiorly and movable therein, and means for moving the presser head within the casing. 85

In testimony whereof I affix my signature,

FRANCIS M. C. USHER.
